UNITED STATES PATENT OFFICE.

JOSEPH BECKER, OF WASHINGTON, DISTRICT OF COLUMBIA.

AUTOMATIC-FOCUSING CAMERA.

1,190,214.

Specification of Letters Patent.

Patented July 4, 1916.

Application filed November 7, 1911. Serial No. 659,021.

To all whom it may concern:

Be it known that I, JOSEPH BECKER, a citizen of the United States, residing at Washington, in the District of Columbia, 5 have invented new and useful Improvements in Automatic-Focusing Cameras, of which the following is a specification.

The present application, identified for convenience of reference as "Case U," relates to automatic copying or enlarging cameras having the lens, the object plane and the image plane connected by focusing gear of the radial cam type first disclosed by Carpentier in his German Patent No. 15 102,004, issued 1899.

The main object of the invention is to establish, for all classes of radial cam focusing gear, principles of construction, regulation and adjustment, which shall be in 20 strict conformity with the Gaussian theory of lenses. Such principles were first disclosed, as applied to linkage focusing gear, in my prior applications, Case K, Serial No. 269,048, filed July 10, 1905, now Patent No. 25 1,103,342; and Case O, Serial Nos. 542,842 and 793,262, filed October 3, 1913, now Patent No. 1,103,343.

In the accompanying drawings: Figure 1 is a side elevation of a preferred form of 30 the camera, showing the bed and mechanism sectioned on the vertical plane 1, 1 of Fig. 2; Fig. 2 is a plan; Fig. 3 is a vertical section on the broken plane 3, 3 of Fig. 2; Fig. 4 is an enlarged isometric perspective of the 35 combined slide and pivot pin which is used for the end frames; Fig. 5 is a sectional elevation of the adjustable lens frame pivot. Fig. 6 shows my complete form of radial cam focusing gear, and Fig. 7 is a corresponding simple form; Figs. 8 and 9 are, respectively, similar to Figs. 6 and 7, but show a more general form of gear in which the 40 end frame connecting points A, A' are offset to move in different parallel planes; Fig. 45 10 is an inverted plan of an enlarging camera provided with my unsymmetrical compound rectangular cam which constitutes in itself an original and entirely novel mechanical movement; Fig. 11 is an enlarged fragmentary section of Fig. 10 on the plane determined by the axes A and D; Figs. 12 to 20, all drawn to the scale seen near "Inventor," are diagrams of arrangements presenting special points of interest. 55 Referring to Figs. 1 to 5, the bed of the camera comprises two parallel rails 10, 11 connected at their ends by cross heads 12, 13

and at their middle point by a cross-bar 14 which has a vertical bore 15 (Fig. 2) the axis of which is indicated by D. Cross-bar 14 is extended to form a projecting arm 16 which is provided with a uniformly wide slot 17, the median plane of which is perpendicular to the rails 10, 11 and contains the axis D of bore 15. The walls of slot 17 should be true and sufficiently well finished to provide a smooth fit for the shank 18 of a bolt whose head 19 is adapted to bear squarely on the upper surface of arm 16. The axis C of this bolt and axis D before 70 mentioned are parallel and remain in the same transverse plane, but the distance CD (Fig. 2) between them is variable to the extent permitted by the length of slot 17.

The lower projecting end of the bolt 75 shank 18 passes, first, through a smoothly bored sleeve 20 having an integral upper flange or seat 21; then, through a wide washer 22; and finally into nut 23. By turning nut 23 sleeve 20 is firmly clamped to arm 80 16 to serve as a downwardly projecting stud or axle for the hub 24 of a cam disk 25. The hub 24 is made a trifle shorter than the space between flange 21 and washer 22 to insure that the clamping action of the bolt 85 shall be confined to the sleeve and washer and shall not interfere with the freedom of rotation of the hub and disk. The latter is provided with two rectangularly disposed radial slots 26 and 26'. Slot 26 slidingly engages the squared head 27 of a pintle 28; and slot 26' similarly engages the squared head 27' of a pintle 28'. The two squared heads 27, 27' are, respectively, provided with flanges 29, 29' which serve as supports for 90 the cam disk 25 while pivot 20 of the latter is being adjusted and mounted. Pintle 28 is revolvably held in carriage 30 by a split pin 31 so that its head may turn to follow the varying inclinations of slot 26, and it is 100 adjustably connected with the object frame O by a clamp bolt 32, as fully set forth in my said prior applications. Pintle 28' is similarly held in carriage 30' by a split pin 31' so that its head may turn to follow the 105 varying inclinations of slot 26', and it is adjustably connected with the image frame I by a clamp bolt 32'.

The axis of the left pintle 28 is indicated by A and the axis of the right pintle 28' by 110 A'. Axes A, D and A' correspond in every particular to the similarly lettered axes of my said prior applications, Case K and Case O, and the pintles 28, 28' are, therefore, ad-

justed in proper relation to their respective frames by focusing on infinity, as fully explained in my said prior Cases K and O, where substantially the same type of camera is shown in Figs. 19 to 22.

It may be well, however, to describe the mode of adjustment and regulation in full, as follows: Pintles 28, 28' and cam disk 25 are removed. Carriage 30 is moved up to bring its axis A into coincidence with axis D and the coincidence of the axes is insured by reinserting pintle 28; then bolt 32 is loosened to free frame O which is then focused on an infinitely distant object to the right and bolt 32 is retightened to clamp O in fixed relation to its carriage 30 and to axis A, after which pintle 28 is withdrawn and frame O is slid back with its axis A properly adjusted. Carriage 30' is now moved up to bring its axis into coincidence with axis D and the coincidence of the axes is insured as before by reinserting pintle 28 or 28'. Then bolt 32' is loosened to free frame I which is then focused on an infinitely distant object to the left and bolt 32' is retightened to clamp frame I in fixed relation to its carriage 30' and to its axis A', after which the pintle used at D is withdrawn and frame I is slid back with its axis A' properly adjusted.

The only thing that now remains to be done is to determine the distance CD; and this is done automatically, after having focused one of the end frames I or O on the other, as follows: Clamp one of the end frames, say O, at any desirable intermediate point of the rails 10, 11 and having focused the other frame I sharply on O clamp I also, to the rails 10 and 11 in its focused relation to O. Now, having passed the pintles 28, 28' up through their slots in disk 25, remount the pintles in their respective carriages and fasten them by inserting their split pins 31, 31'. Cam disk 25 is now held up by the two pintles 28, 28' alone, and as the carriages 30, 30' are clamped to the rails cam disk 25 may be slid around freely on the pintles and its hub 24 will, for known geometrical reasons, be constrained to move around in the semi-circle described on A A' as diameter. Having then dropped the bushing or sleeve 20 into the hub, the cam 25 is moved around until the bore of sleeve 20 is seen to register with the slot 17. Bolt 18, 19 is then inserted and the sleeve is then clamped to arm 16 by slipping on washer 22 and firmly screwing on the nut 23. The carriages 30, 30' may now be unclamped from the rails and the apparatus will be found to be fully regulated and adjusted ready for use without even knowing the focal length of the lens used or the extent, sign, or location of the internodal space NN' as all these lens dimensions have duly and automatically been allowed for in making the several adjustments.

The structural conditions may, therefore, be summed up as follows: Noting that the distances of the pivot axis C from the principal focal planes F, F' of the lens are exactly the same as those of axis D, and designating these distances by x and x' as in my said prior applications, I say that the distances x and x' of the lens axis C from the principal focal planes F and F', should respectively, be equal to the distances m, m' of the end frame axes A, A' from their respective image planes P, P'. Or in symbols

$$\begin{aligned} m &= x \\ m' &= x' \\ (m+m') &= (x+x') = F F' = (2f+NN') \end{aligned} \quad 80$$

where any one of the elements m, m', x or x' considered *per se* may have any desirable plus or minus value, regardless of the value of f . The correctness of the principles here advanced are made self evident by the aid of my complete form of radial cam focusing gear.

The complete form, which presents the advantage of determining co-varying mechanical space elements AD, D'A' corresponding directly to the simultaneously co-varying Newtonian space elements PF, F'P' of the lens, is shown in Fig. 6. Here 50 is a slotted plate representing the rails or bed of an enlarging camera having its lens 51 mounted in fixed position with relation to the bed 50.

The conjugate planes P, P' of the lens are connected with pins A, A' which slide in the slots 52, 52'. Pin A is moved by the radial cam 53, pivoted at C in the focal plane F, at a distance CD equal to the focal length f from the path of A; and similarly pin A' is moved by the radial cam 53' pivoted at C' in the focal plane F', at a distance C'D' equal f from the path of A'. Bar 53 has an extension CE and bar 53' an equal extension C'E' bent around to form a right angle A'C'E', and the ends of these arms are connected by a link EE' equal to CC' (or FF') and forming an articulated parallelogram CC'E'E which obliges AC and A'C' to remain perpendicularly to each other throughout all their movements, so that the right angled triangles ADC and C'D'A' are and at all times remain similar with the vertical side CD in the left triangle corresponding to the horizontal side D'A' in the right hand triangle, and, therefore,

$$\frac{AD}{DC} = \frac{C'D'}{D'A'}$$

or

$$\frac{AD}{f} = \frac{f}{D'A'}$$

whence

$$AD \cdot D'A' = f^2 \quad (2)$$

Now as the variable PF is mechanically

kept equal to AD , and the variable $F'P'$ is likewise mechanically kept equal to $D'A'$ we always have

$$\begin{aligned} 5 \quad PF &= AD & (3) \\ F'P' &= D'A' & (4) \\ PF \cdot F'P' &= AD \cdot D'A' & (5) \end{aligned}$$

and this in view of equation 2 yields

$$10 \quad PF \cdot F'P' = f^2 \quad (6)$$

which is Newton's formula or equation 4 of my said Case K.

15 A simple form of slotted lever 63, 63', Fig. 7, is derived from Fig. 6 by reducing EE' and CC' to zero, which is done by shifting triangle CAD to the right through distance m (equal x), and triangle $C'D'A'$ to the left through the distance m' (or x') equal to FF' minus m . This is the Carpentier focusing gear improved to act in strict conformity with the Gaussian theory of lenses.

20 If any two equal links AB , BA' be added in Fig. 7, no variation can be produced in the distance BD by actuating the lever 63, 63'; so that a third link BD may be inserted to form a linkage gear such as disclosed in Fig. 1 of my Case K. The two focusing mechanisms, therefore, coöperate, constituting 25 a combined Becker-Carpentier focusing mechanism.

The invariability of distance BD may be demonstrated as follows:

30 Let the known length of the two equal links be

$$AB = BA' = a$$

and let the unknown distance from B to D be z . Moreover, let the constant product 40 variables AD and DA' be

$$\begin{aligned} AD &= u \\ DA' &= v \end{aligned}$$

so that

$$45 \quad uv = CD^2 = f^2$$

Then the left triangle ABD yields

$$z^2 = a^2 + u^2 - 2au \cos DAB$$

But

$$50 \quad 2a \cos DAB = AA' = AD + DA' = u + v$$

so that

$$\begin{aligned} z^2 &= a^2 + u^2 - (u + v)u \\ &= a^2 + u^2 - u^2 - uv \\ &= a^2 - uv \end{aligned}$$

or

$$z^2 = a^2 - f^2$$

whence

$$60 \quad z = \sqrt{a^2 - f^2}$$

and this is a constant, as a (or AB) and f (or CD) are both rigid structural elements.

Fig. 8 shows my complete form with the paths A and A' offset. Here CD and $C'D'$ 65 are unequal, but their product as before is

equal to the square of the focal length f of the lens. The two triangles ADC , $C'D'A'$ are, and remain, similar yielding

$$\frac{AD}{DC} = \frac{C'D'}{D'A'} \quad 70$$

Whence, as before, in Fig. 6

$$AD \cdot D'A' = f^2 \quad (7)$$

Here again, as in Fig. 6, the variable PF 75 is mechanically kept equal to AD , and the variable $F'P'$ is mechanically kept equal to $D'A'$ so that we always have.

$$\begin{aligned} 80 \quad PF &= AD & (8) \\ F'P' &= D'A' & (9) \\ PF \cdot F'P' &= AD \cdot D'A' & (10) \end{aligned}$$

and this in view of equation 7 yields

$$85 \quad PF \cdot F'P' = f^2 \quad (11)$$

which is identical with equation 6 above and with Newton's formula or equation 4 of my said Case K. These equations 7 to 11, being identical with equations 2 to 6, above, prove that the focuser of Fig. 8 is an exact mechanical equivalent for the focuser of Fig. 6.

From Fig. 8 is directly derived the simple form of Fig. 9, which is the type of rectangular cam shown in French patent of Stevens, No. 330,565 of March, 1903, and in 95 Figs. 7 and 8 of British patent to Cook, No. 12,734 of 1904.

The different simple forms of focusing gear described or referred to may be distinguished by the relative positions of the axes of their three connecting points, with respect to the longitudinal plane drawn through axis A parallel to the slideways in the bed of the camera. In the Becker (my) linkage (BA , BD , BA' , Fig. 7) the lens 100 point or axis D and the image points or axes A and A' will all lie in the same longitudinal plane. In the Carpentier gear (63, 63', Fig. 7) the image point or axis A' will be in the same longitudinal plane with A , but 105 the lens point, or axis C , will be offset to lie in another longitudinal plane. In the Stevens-Cook gear the three connecting points or axes A , C , A' will lie in three different longitudinal planes in the order C , A , A' or C , A' , A . This same classification applies to the compound forms and, therefore all types shown or referred to, to wit: Becker, Carpentier, or Stevens-Cook, however much they may differ as to the lateral arrangement of their three connecting points, must, it is now seen, agree exactly in the longitudinal arrangement of such points or axes, and to bring this common principle out as clearly as possible the separation of the principal foci F , F' and the focal length f of the lens are made the same in Figs. 1, 2 and 6 to 10 and the conjugate planes P , P' in the same figures are set to copy double size so that PF is one-half of f , while $F'P'$ 130

is twice f . Figs. 1, 2, 6, 7, 8, 9 and 10 could, therefore, all be superposed so as to bring their six points P, F, N, N', F', P' into exact coincidence.

5 The last described or Stevens-Cook form 83, 83', Fig. 9, is shown again in Fig. 10 as used in a working camera which is also provided with my novel unsymmetrical duplicating 93, 93'. The bed 10, 11, 12, frames O, 10 L, I, and most other features are substantially the same as in Figs. 1, 2, 3 and 5, but the carriages 100, 100' have their axes A, A' offset to move in planes through the bores D, D' in the middle bar 101 which has two 15 slotted extensions 102, 103.

Points C, C' are found on the circle described on A, A' as diameter, and the center of this circle which is midway between A and A' must be equidistant from D and D' 20 so that the lever arms AC and AC' must be unequal in all positions of the frames and levers. Arms A'C and A'C' are also unequal for the same reason.

The two slotted levers 83 and 93, therefore, are not to be considered as mere duplicates, but as constituting in fact an entirely novel focusing gear which is also capable of use as a mechanical movement for transmitting straight line motion from A on one line 30 AD to A' on an offset parallel line D'A'.

The end frame connecting pins in this Fig. 10 are shown as mere round pins for clearness. The enlarged section Fig. 11 taken on the plane AD of Fig. 10 shows 35 their exact construction. The spindle 96 with squared head 97 of greater width than the spindle carries a second squared slide block 98 which turns independently on the spindle 96, and the spindle is held in place 40 on its carriage 100 by a split pin 99.

The rules for adjusting and regulating this device are precisely the same as those given for the form of Figs. 1 to 5. The operator, therefore may insert his lens and 45 proceed to adjust the device as indicated for Figs. 1 to 5, and within a few minutes he may use the camera to copy, reduce or enlarge at any desired scale and he will be able to do all this without ever knowing the 50 focal length of the lens used or the value of any other dimension that enters into the combination.

Other types.—It is impractical to illustrate the many different forms that can be 55 derived by simply changing proportions, and nearly all "complete forms" are needlessly complicated. The following "special cases," however, deserve to be mentioned. In addition to the complete forms of Figs. 6 and 8, and the simple or rectangular cam forms of Figs. 7 and 9, there exists an intermediate more general class or type, Figs. 12 and 13 respectively derived from the complete forms, Figs. 6 and 8, by making shifts 60 m and m' such that their sum ($m+m'$) or

($x+x'$) shall differ from the distance FF' by an amount FF' minus ($x+x'$) which may be either positive or negative and which represents the length EE' of the link that has to be used. It is only when EE' equals 70 zero that we obtain the simple forms.

A still more general form, Fig. 14 or Fig. 15 might be derived by shifting the triangles ADC, C'D'A' vertically as well as horizontally, and in the forms thus derived from 75 Fig. 8 the vertical shift may be made just sufficient to bring paths AD, D'A' into alinement, as in Fig. 15.

Two remarkable intermediate forms, Figs. 16 and 17 constituting in fact a distinct 80 type, are derived the one from Fig. 6 and the other from Fig. 8, by making m and m' both equal to f so that C falls into the transverse or principal plane through N, and C' into the principal plane through N', the 85 link E, E' being equal to N, N'.

Two remarkable simple forms, Figs. 18 and 19 are similarly derived one from Fig. 6 and the other from Fig. 8, by making m equal to f and m' equal to f plus NN'. This 90 reduces the distance CC' and EE' to zero and brings the single remaining lens pivot C into the principal plane through N.

Fig. 20, in which m' , equal to x' , equals zero, is a diagram of the exact arrangement 95 shown, but imperfectly described, by Stevens in French Patent 330,565, of 1903 which was referred to hereinbefore in describing Fig. 9. Figs. 12 to 20 are all drawn to the scale seen over "Inventor" and they all contain the same lens whose focal length FN or N'F' equals 12 centimeters and whose interfocal space FF' equals 27 centimeters. In Figs. 12 to 19 the Newtonian space AD or PF is 6 centimeters and the Newtonian 100 space F'P' or D'A' is 24 centimeters, so that the copying factor n equals 2. In Fig. 20 the Newtonian space AD or PF is 8 centimeters and the Newtonian space D'A' or F'P' is 18 centimeters, so that the copying 105 factor n equals 3/2. In Figs. 12, 13, 14 and 15 the shift m or x is 3 centimeters; and the shift m' or x' is 8 centimeters. In Figs. 16 and 17 the shifts m or x and m' or x' are all equal to f , or 12 centimeters. In Figs. 18 110 and 19 the shift m or x is 12 centimeters, but the shift m' or x' equals the distance from N to F', or 15 centimeters. In Fig. 20 the shift m or x equals FF', or 27 centimeters; and the shift m' or x' is *nil*. All 115 shifts herein shown are positive. In each of the Figs. 12 to 20 the product CD.D'C' being equal to f^2 , or 12 by 12, must be 124. Thus in Figs. 12, 14, 16 and 18 it is 12 by 12; in Figs. 13, 15, 17, 19 it is 9 by 16; in Fig. 20 it is 16 by 9; whole number values being 120 used throughout to facilitate verifications, both by scale and computation.

NOTE 1.—The kinematic effect produced 125 by a "rectangular radial cam" such as shown

in Figs. 2 or 7 is substantially the same as that produced by the "circular cam" shown in Fig. 2 of my Case T, now Patent 1,142,295 issued June 8, 1915.

- 5 NOTE 2.—The articulated parallelograms EE'CC' of Figs. 6, 8, and 12 to 17 considered *per se*, are pure linkages which disappear entirely in the simple radial cams of Figs. 2, 7, 9, 10, 18, 19 and 20.
- 10 NOTE 3.—A camera built in accordance with German Patent 102,004 of 1899 to Carpentier is of the type seen in my Fig. 7, with m , equal m' , equal FN; and with pivot C set in the vertical plane containing the 15 "optical center" of the lens, at a distance CD equal FN from the slideway of pins A, A'. In accordance with my invention, however, to make m equal m' , we must make x equal x' and we should have

$$m = x = x' m' = \frac{1}{2} FF' = FN + \frac{1}{2} NN'$$

- or m , equal m' , equal FN plus one-half of NN', instead of m equal FN; and the pivot C should be set exactly midway between the 25 two principal planes N, N', even when the co-called "optical center" is not situated midway between points N and N'.

- NOTE 4.—A camera built in accordance with German Patent 237,380, issued August 30 7, 1911, to Kilian is substantially of the type seen in my Fig. 7, with dimension m' arbitrary as in Fig. 7. Kilian, however, makes the sum m plus m' equal to twice FN instead of equal to twice FN plus the internodal space NN', as it must be in accordance with my invention.

- NOTE 5.—Where the lens used happens to have an internodal space NN' that is *not*, the 40 Carpentier rule of construction, given above in Note 3, and the Kilian rule of construction, given above in Note 4, lead to results that are not in disagreement with my rule of construction as partly embodied in my equation 1; but the advantage of my rule of construction is that it is exact for all lenses or all possible values of the internodal space NN', and that it is exactly and automatically satisfied by the use of the method of adjustment and regulation disclosed in my 45 cases K and O; so that, it practically does away with all rules of construction. That is to say, all unknown structural dimensions of a radial cam focuser are, in view of my said cases K and O, automatically determinable by means of three simple focusing operations, without ever knowing such structural dimensions or the focal length f of the lens used and without knowing the extent, sign, 50 or location of the internodal space NN'.

60 What I claim as my invention and desire to secure by Letters Patent is:

1. A copying or enlarging camera comprising a support for an object plane, a support for a lens, and a support for an image receiving plane, and automatic focusing

mechanism of the radial cam type with connections to the said three supports for relatively moving two of such supports with relation to the third and having two of such connections made freely adjustable in the 70 direction parallel to the slideway in the camera bed, to secure desired changes in the longitudinal dimensions of such connections; also a transverse adjustment to adapt the device for use with different lenses. 75

2. The combination with an automatic copying or enlarging camera having a rectangular cam focusing gear; of means for adjusting its end frame pintles with relation to their respective conjugate planes in planes 80 parallel to the slideway of the camera; and means for adjusting the lens pivot in a plane perpendicular to the slideway of the camera.

3. A copying or enlarging camera comprising: a support for the object; a support 85 for the lens and a support for the image receiving surface, such three supports being virtually: a support for the object plane P; a support for the focal planes F, F' and a support for the image plane P'; such camera 90 having the supports of its left focal planes F and P connected by a radial cam pivoted to F at a distance x from F and acting on a point A mounted in fixed relation to plane P at a distance m , equal to x , from P; said 95 same camera also having the supports of its right hand focal planes F' and P' similarly connected by a radial cam pivoted to F' at a distance x' therefrom and acting on a point A' mounted in fixed relation to P' at a distance m' , equal x' , from P'; the distance of 100 the cam pivots from the paths of their respectively controlled points A and A' being such as to form a constant product equal to the square of the focal length of the lens; 105 and means to oblige the two radial cams to turn equally in perpendicular relation.

4. A copying or enlarging camera comprising: a support for the object, a support for the lens and a support for the image receiving surface, such three supports being virtually: a support for the object plane P'; a support for the focal planes F, F' and a support for the image plane P'; such camera 110 having the supports of its left focal planes F and P connected by a radial cam pivoted to F at a distance x from F and acting on a point A mounted in fixed relation to plane P at the distance m , equal to x , from P; said same camera also having the 115 supports of its right hand focal planes F' and P' similarly connected by a radial cam pivoted to F' at a distance x' therefrom and acting on a point A' mounted in fixed relation to P' at the distance m' , equal x' from P'; the distance of the cam pivots from the 120 paths of their respectively controlled points A and A' being such as to form a constant product equal to the square of the focal length of the lens; and means to oblige the 125

two radial cams to turn equally in perpendicular relation, said means consisting in an articulated parallelogram.

5. The combination with a copying or enlarging camera having rectangular cam focusing gear of the type having the end frame connecting axes A, A' offset in different planes parallel to the slideway of the camera; of a second rectangular cam having its 10 pivot symmetrically disposed with relation to the pivot of the first mentioned cam and adapted to act directly on the same said axes A, A'.
6. The combination with a copying or en-

larging camera having a rectangular cam 15 focusing gear with its lens pivot freely adjustable in the direction perpendicular to the slideways and its two end frame pivots freely adjustable with reference to their respective image planes in the direction parallel to the slideways.

In testimony whereof, I have signed my name to this specification in the presence of two subscribing witnesses.

JOSEPH BECKER.

Corrections in Letters Patent No. 1,190,214.

It is hereby certified that in Letters Patent No. 1,190,214, granted July 4, 1916, upon the application of Joseph Becker, of Washington, District of Columbia, for an improvement in "Automatic-Focusing Cameras," errors appear in the printed specification requiring correction as follows: Page 5, line 20, separate "m'" from "x'" and insert the sign of equality so that the line shall read—

$$m = x = x' = m' = \frac{1}{2} FF' = FN + \frac{1}{2} NN'$$

same page, line 26, for the compound word "co-called," read *so-called*; and that the said Letters Patent should be read with these corrections therein that the same may conform to the record of the case in the Patent Office.

Signed and sealed this 25th day of July, A. D., 1916.

[SEAL.]

F. W. H. CLAY,
Acting Commissioner of Patents.

Cl. 88—24.
